CLAIM

The ornamental design for a foldable charging cable, as shown and described.

DESCRIPTION

FIG. 1 is a perspective view of a foldable charging cable in a folded configuration, showing each end portion with a connector;

FIG. 2 is a right side view of the foldable charging cable of FIG. 1;

FIG. 3 is a left side view of the foldable charging cable of FIG. 1;

FIG. 4 is a top plan view of the foldable charging cable of FIG. 1;

FIG. 5 is a bottom plan view of the foldable charging cable of FIG. 1;

FIG. 6 is an upper plan view of the foldable charging cable of FIG. 1;

FIG. 7 is a lower plan view of the foldable charging cable of FIG. 1;

FIG. 8 is a perspective view of the foldable charging cable of FIG. 1, but illustrating the foldable charging cable in an unfolded configuration, such that each end portion, in the unfolded configuration, shows an additional connector positioned in each end portion;

FIG. 9 is a perspective partial view of the unfolded configuration of the foldable charging cable of FIG. 8, but showing only the unfolded end portion of the right side; and, FIG. 10 is a perspective partial view of the unfolded configuration of the foldable charging cable of FIG. 8, but showing only the unfolded end portion of the left side.
